(57) **CLAIM**

The ornamental design for a skateboard tool, as shown and described.

DESCRIPTION

FIG. 1 is a perspective view of a skateboard tool showing my new design;

FIG. 2 is the second perspective view thereof;

FIG. 3 is the third perspective view thereof;

FIG. 4 is a front elevational view thereof;

FIG. 5 is a rear elevational view thereof;

FIG. 6 is a left elevational view thereof;

FIG. 7 is a right side view thereof;

FIG. 8 is a top plan view thereof;

FIG. 9 is a bottom plan view thereof; and,

FIG. 10 is an exploded perspective view thereof.

The broken lines in the figures are for the purposes of illustrating portions of the skateboard tool, which form no part of the claimed design.
